GLOVE CONSTRUCTION

Leo Newbower, Gloversville, N. Y., assignor to
 Edna Higier and Julius Higier, doing business
 as The Super Glove Company, Johnstown, N. Y.

Application February 17, 1950, Serial No. 144,651

5 Claims. (Cl. 2--169)

1

The present invention relates to a glove construction and more particularly to a new and improved glove construction possessing new lines of construction in which the main panel or trunk of the glove and the thumb panel are integrally formed with one another.

The ordinary method employed at the present time in the commercial production of gloves is to first cut the main panel or trunk from a suitable piece of material as a separate unit and then cut the thumb panel from the material, likewise, as a separate unit. The two separate panels are then fitted to one another and sewed in this position to form the glove blank from which the ultimate glove will be formed. To form the glove, the blank is folded along its various closing lines and then sewn along such lines forming thereby the completed glove. This operation is repeated for each glove. It will be readily observed that the lines of construction of the glove are quite limited in that the presence of two separate seams in each glove prevents any material modification of the component parts of the glove. It has been found that gloves prepared by the above-described method possess many serious objections and disadvantages which have been found undesirable.

One principal objection attendant to this prior method is that it is extremely difficult to produce a glove which will conform perfectly with the anatomical outline of the human hand when the seam uniting the thumb panel to the main panel is present. The importance of producing a glove possessing anatomical conformation cannot be over-emphasized since if the glove does not possess this characteristic the wearer does not have the complete and free use of his hand when encased in the glove.

Another objection to such prior art gloves is that the presence of the seam between the thumb panel and the main panel permits only one line of construction and also makes it an impossibility to produce a pair of perfectly matched gloves since so many separate cuttings and fittings are required. Moreover, the seam present in these gloves must be, of necessity, at a point where the greatest strain and wear is imparted to the glove. As a result, such gloves possess a weak point at the place where the greatest strength and reinforcement is required and consequently, such prior methods of construction result in a glove possessing a rather short wearing life.

Such prior methods result, also, in high production costs during the manufacture of the gloves since a large amount of wastage of the material used will be encountered due to the

2

various separate cuttings and fittings of the many individual pieces. Moreover, the labor costs are relatively high due to the time required for the matching and sewing together of the various separate pieces. Likewise, the resulting glove does not present or possess an attractive appearance with resulting eye appeal to a prospective buyer due to the many unsightly seams.

There have been some isolated attempts heretofore to construct a one-piece glove which would not possess the above enumerated disadvantages. These attempts, however, have, in every instance, proved unsuccessful from a commercial standpoint since the completed glove has either had a thumb member formed by sewing two or more appendices of the main panel together or the thumb was incongruous with the anatomical function of the hand and has had extremely poor visual appeal. Consequently gloves of this type heretofore made have possessed no better characteristics as those gloves made in the manner previously described.

It is, therefore, a principal object of the present invention in the elimination of the above-mentioned objections encountered in prior art gloves to provide a glove possessing new lines of construction and having materially increased structural strength with resulting greater wearing life for the glove.

Another object is the providing of a glove construction in which the trunk or main panel and the thumb panel are integrally formed with one another as a single unit with a resulting increase in the strength and wearing life of the glove.

Still another object is the providing of a glove which conforms perfectly with the anatomical outline of the human hand thus permitting complete freedom of movement of the gloved hand as well as permitting the production of a substantially perfect matched pair of gloves.

Still another object is the providing of a glove which possesses considerable eye appeal under all conditions and which is manufactured at a cost much less than that heretofore found necessary.

Other and additional objects and improvements will become apparent from the annexed drawings and the description to be hereinafter given.

To the accomplishment of the foregoing and related ends, the present invention then consists of the means hereinafter fully described and particularly pointed out in the claims, the annexed drawings and the following description setting forth in detail certain means in the carrying out

of the invention, such disclosed means illustrating, however, but one of various ways in which the principle of the invention may be employed.

The present invention is illustrated in the accompanying drawings in which:

Figure 1 is a perspective view of a completed glove made in accordance with the present invention;

Figure 2 is a perspective view of a glove blank made in accordance with the present invention with certain portions thereof folded to illustrate the closing of the glove blank;

Figure 3 is a sectional view taken on lines 3—3 of Figure 1; and,

Figure 4 is a developed view of a glove blank 15 made in accordance with the present invention prior to folding.

Referring now in detail to the annexed drawings and with particular reference to Figure 4, the one-piece glove blank of any suitable material from which the completed glove in accordance with the present invention is to be formed comprises a central back panel 10, an integral side panel 11 functioning as the palm of the glove, and an integral thumb panel 12. The side panel 11 is adapted to be folded over the main panel 10 along folding line 13 and the thumb panel 12 is adapted to be folded along folding line 14 to meet the folded side panel 11.

The main panel 10 is provided with four slit finger pieces 15, 16, 17 and 18 which will function as one-half of each of the ultimate fingers of the glove. The side panel 11 is provided with four complementary mating slit finger pieces 15', 16', 17' and 18', the mating of these with the finger pieces of the main panel 10 forming the four complete finger members of the glove. The thumb panel 12 comprises complementary members 19 and 19', respectively, which are adapted to be folded along folding line 20 to form the thumb member of the glove. The folded thumb panel 12 is adapted to be folded in this position along folding line 14 to be in position to be joined to the folded side portion 11 (see Fig. 2). It will be noted that the folding lines 13, 14 and 20 are all parallel to one another to insure the proper mating of all the members.

The side panel 11 which, when mated with main panel 10, forms the palm of the glove, is provided with an integrally formed gusset 21 depending from the bottom of the index finger portion 15'. The triangular shaped gusset 21 is joined to the extension of the index finger portion 15' at a point substantially above the heel of the hand, this point being indicated by line 22 which is shown as cutting straight across the face of the glove blank. The thumb panel 12 has its member 19' provided with a diagonal slit 23 extending diagonally downwardly from the folding line 14 down to line 22. That is to say that the base from which the gusset 21 extends downwardly from the side panel 11 and the bottom point of the diagonal slit 23 in the thumb panel 12 end on line 22. It should be particularly noted that the remainder of the glove lying below line 22 is symmetrical in form and shape whereas that portion of the glove blank lying above line 22 has its various parts in parallel relationship to one another. This arrangement is important in order to insure the completed glove having the proper symmetry and fit.

As shown in Fig. 4 the glove blank made in accordance with my invention forms in one piece the palm, the back and the thumb coverings keeping the part for the thumb and the part

70 for the palm parallel to the main part of the back. In other words, the thumb panel and the palm panel are folded along parallel lines to form the glove. It is quite important in the present invention that the folding lines of the axis of both the main panel 10 and the thumb panel 12 be parallel in order to insure perfect uniformity and the proper fit. The two finger portions 15 and 15' for the covering of the index finger are the outer edges of the main part of the glove blank and the palm portion 15' is slightly wider than the back portion 15 to guarantee a uniform appearance of all fingers when viewed from the back.

The following description describes in detail the forming of the completed glove. After each of the panels above described have been mated and the fingers have been closed in the usual manner by inserting double strips of material (fourchettes) 24 between side panel 11 and the main panel 10, the index finger parts 15 and 15' are first connected on the side situated toward the finger members 16 and 16' with one-half of a fourchette and finally closed on the side situated toward the thumb panel 12. With this closing of the index finger, the closing of the entire glove has been started. That means that the outer edges of the main panel 10 and the side panel 11 are joined starting on the tip of the index finger members 15 and 15', following it beyond its main joint and leading to point 25 in Fig. 4 just above gusset 21. This describes an arcuate curve which parallels the curve of the anatomical structure of the human hand between the thumb and index finger. From point 25, the closing process incorporating gusset 21 in the structure moves along the line where the side panel 11 is provided with the gusset 21 to point 26 where it meets the closing seam on the thumb panel 12 and then continues without interruption on the other side of the gusset 21 to point 28 and finally ends on top of the glove.

It will be apparent to those skilled in the art that my new and improved construction allows the use of any width of flair without harming its perfect fit. The edges of the panel beyond the thumb are substantially symmetrical and of the same over-all length, which warrants trouble-free closing and symmetrical flairs on both sides of the finished glove. The thumb piece requires only one closing seam on the inner side of the thumb which gives it a highly improved flexibility. The unity of material eliminates poor matching and results in reduced production costs, because cutting of only one piece of material and less overall seams permit saving in labor. Gloves made according to my present invention give very satisfactory wear since they have none of the closing seams exposed to those parts of the glove where the greatest strain or wear is to be experienced.

Having described my invention in detail, I therefore claim:

1. A one-piece glove blank comprising a central panel having four slit finger pieces, an integral side panel formed therewith and having four finger pieces complementary with the finger pieces of said central panel, the index finger piece of said side panel having a depending gusset secured to its bottom half thereof, said side panel being adapted to be folded over said central panel, and a thumb panel integrally secured to said central panel and comprising a complete thumb piece adapted to be folded along a center line, the folded thumb piece being

adapted to be folded over the central panel, said thumb piece being provided with a diagonal slit extending downwardly from the line along which the thumb piece is folded over the main panel to a point lying substantially along the same line from which the gusset depends, said side panel, central panel, and thumb panel being folded along lines which are substantially parallel to one another.

2. A one-piece glove comprising a main panel having four slit finger pieces, a side panel having four complementary slit finger pieces integrally secured to and folded over said main panel, fourchette strips uniting the slit finger pieces of each of said panels to one another along their outer edges, a thumb panel integrally secured to said central panel, said thumb panel having front and back mating portions folded along a center line to form the complete thumb piece, a gusset depending from the free side of said side panel, said thumb piece having a diagonal slit extending downwardly from the line along which the thumb piece is folded over the main panel to a point lying substantially along the same line from which the gusset depends, and fourchette strips for securing the completed thumb piece to said gusset and said side panel, said side panel, central panel, and thumb panel being folded along lines which are substantially parallel to one another.

15

10 5. A glove in accordance with claim 2 wherein in the gusset is triangular in shape and the portion of the thumb panel more remote from the main panel curves inwardly for receiving the gusset.

15 10 5. A glove in accordance with claim 2 wherein in the gusset is triangular in shape and the portion of the thumb panel more remote from the main panel curves inwardly for receiving the gusset.

3. A glove blank in accordance with claim 1 wherein the index finger piece of said side panel is wider than the corresponding mating finger piece of said central panel.

5. A glove in accordance with claim 2 wherein the index finger piece of said side panel is wider than the corresponding mating finger piece of said central panel.

10 5. A glove in accordance with claim 2 wherein in the gusset is triangular in shape and the portion of the thumb panel more remote from the main panel curves inwardly for receiving the gusset.
